CENTRIFUGAL AIR COMPRESSOR

Adolph L. Berger, Dayton, Ohio

Application October 20, 1943, Serial No. 506,979

4 Claims. (Cl. 230—127)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to centrifugal air compressor for high speed turbo-blowers and pumps, and has for an object, means to reduce or eliminate turbulence in the fluid being pumped as it leaves the centrifugal impeller member of the pump and passes into the peripheral portion of the blower casing.

Centrifugal impellers of the turbo-blower type, used for supercharging aircraft internal combustion engines at high altitudes operate at extremely high speeds and the air being pumped or compressed travels through the impeller at an extremely high velocity; and it is difficult in the usual centrifugal pump of the turbo-blower type to effect a smooth and uniform fluid flow, particularly at the tip or periphery of the impeller member, and in the zone just beyond the impeller periphery where the compressed fluid passes into the annular fluid collection and delivery chamber of the impeller casing, which has the discharge opening leading to the intake manifold or other fluid delivery point.

One reason for the non-uniform flow is that the space between the side plate or shrouds of the impeller member and the adjacent sides of the casing usually constitutes a low pressure area, and the frictional drag or skin friction of the fluid between the sides of the impeller shrouds throws the air out of this space along the sides of the impeller while the stationary adjacent surfaces of the casing each allow a film or layer of air to pass back along this latter surface toward the center of the casing, effecting a recirculation of the air between the sides of the impeller and adjacent sides of the casing. This recirculation results in a comparatively low pressure area extending beyond the periphery of the impeller member. The main air flow from between the shrouds of the impeller, as it leaves the impeller is effected by the movement of this recirculated air, and the low pressure area at the tip or periphery of the impeller at opposite sides of the main fluid flow, tends to withdraw or disturb the outer layers of the main fluid delivery from the impeller producing eddies or turbulence in the main flow and with a marked reduction in the efficiency of the impeller. This decrease in efficiency becomes greater as the velocity of the compressed fluid increases.

Auxiliary vanes have been employed on the exterior surfaces of centrifugal impellers of certain

low speed types, used for pumping liquids, to reduce the recirculation between the impeller members and the sides of the impeller casings. These devices do not eliminate or reduce to any appreciable extent the afore-mentioned undesirable eddies and turbulences in the pumped fluid since no provision is made for eliminating the low pressure area at the opposite sides of the impeller in the region of the periphery, disturbing the boundary flow of air between each side of the impeller member and the main fluid flow, as it leaves the periphery or tip of the impeller member. As a result, eddy currents are created in the fluid flow producing the undesirable turbulence and corresponding decrease in impeller efficiency.

Another object is the provision of means preventing recirculation of the fluid being pumped by the impeller member, between the sides of the impeller member and the inner walls of the casing, to obtain a smooth and uniform fluid flow of the pumped fluid as it leaves the impeller member.

A further object is the provision of a high speed shrouded centrifugal impeller for delivering a normal volume of fluid under pressure, having auxiliary pumping means on the impeller for delivering an auxiliary volume of fluid under pressure at opposite sides of the main volume of fluid, to form boundary layers of fluid at opposite sides of the main volume to eliminate the usual reduction of pressure at opposite sides of main fluid volume, due to the skin friction or drag on the fluid at opposite sides of the impeller and casing, and to eliminate the tendency of recirculation of the fluid being pumped between the impeller shrouds, and as the fluid leaves the periphery of the impeller and passes into the casing, to effect a uniform flow, with the elimination of turbulence adjacent the tip or periphery of the impeller member with a corresponding increase in the efficiency of the pump device.

A still further object is the provision of a shrouded impeller member having fluid conducting means for establishing a fluid circulation between the shroud members of the impeller member and the space between the shroud members and the adjacent inner surfaces of the impeller casing, for introducing a portion of the fluid being pumped into the last mentioned space to eliminate or reduce the usual low pressure area between the impeller and casing, particularly at the periphery of the impeller, with corresponding elimination of the eddies and turbulence in the fluid being pumped as it leaves the impeller member that are caused by the said low pressure area at the impeller periphery.

Other objects and advantages of the invention will hereinafter become apparent from the accompanying specification and claims, taken in conjunction with the accompanying drawing, in which like reference characters refer to like parts in the several figures thereof.

Fig. 1 is a vertical sectional view through my improved high speed turbo-blower.

Fig. 2 is an enlarged cross sectional view taken approximately on the plane indicated by the line 2—2 in Fig. 1, disclosing particularly the arrangement of the main and auxiliary impeller blades or vanes on the impeller member.

Fig. 3 illustrates a slightly modified form of impeller member.

Fig. 4 is a cross sectional view taken approximately on the line 4—4 of Fig. 3.

Fig. 5 is a side view of the turbo-blower device.

Referring particularly to Fig. 1 of the drawing, 1 indicates a drive shaft for a high speed turbo-blower device, and 2 a centrifugal impeller member having a central hub portion 3 fixedly secured on the shaft to rotate therewith.

The impeller 2 is formed with front and rear plates or shroud members 5 and 6 respectively, having main impeller vanes or blades 7 extending between the front and rear shroud members 5 and 6. Main fluid inlet ports 8 are formed in the front shroud member 5, and the adjacent, or inner surfaces of the front and rear walls or shroud members 5 and 6 curve rearwardly and outwardly, tapering toward each other and terminate in reduce radial outlet ports 9 located between the vanes or blade members 7.

The impeller member 2 is journaled to rotate within an impeller housing or casing, indicated generally at 10, having spaced annular front and rear walls 11 and 12. The shroud members 5 and 6 of the impeller member rotate in spaced relation to the walls 11 and 12, and the rear wall 12 extends inwardly to a point adjacent the shaft 1 to form a central opening 12' surrounding the shaft 1 in spaced relation thereto for admitting air, or the fluid being pumped, into the space between the rear face of the impeller shroud member 6 and the rear wall 12 of the impeller casing.

The front wall 11 of the casing is formed with a large central opening 13, in register with the inlet ports 8 in the impeller and has an annular opening 13' to introduce air, or the pumped fluid, into the space between front shroud member 5 and the inner surface of the front wall 11 of the impeller casing 10.

The impeller casing is provided with an annular chamber 14, substantially circular in cross section surrounding the periphery of the walls 11 and 12 and is preferably provided with a tangential fluid outlet or peripheral discharge port 14'. Curved annular wall portions connect the respective side walls 11 and 12 with the annular chamber 14, providing for a smooth airflow surface along the inner surfaces of the walls 11 and 12, and into the annular chamber 14.

The periphery or tip portion of the impeller member 2 is located inwardly of the juncture of the side walls 11 and 12 of the impeller casing 10 with the curved annular wall portions 15 and 16, and the inner surface of the annular chamber 14. The shroud members 5 and 6 operate in spaced relation to the inner walls 11 and 12 of the impeller casing and the exterior of the shroud members 5 and 6 are each provided with a suitable number of auxiliary impeller blades or ribs 17 and 18, projecting toward the adjacent surfaces of the walls 11 and 12 of the impeller cas-

ing and terminating in juxtaposed relation to said surfaces.

The auxiliary blades or vane members 17 and 18 cause an auxiliary flow or circulation of the air being pumped to pass through the openings 12' and 13' into the spaces between the impeller member 2 and the inner surfaces of the walls 11 and 12 of the impeller casing as the main air flow of the compressed air, or the pumped fluid medium passes into the inlet openings 8 through the curved throat or chamber and into the space between the plates or shroud members 5 and 6 of the impeller 2, between the main blades 7, and this air or fluid is discharged through the discharge openings 9 at the tip or periphery of the impeller.

The flow of air at opposite sides of the main air flow, caused by the auxiliary blades 17 and 18, produces boundary flows or layers of air at predetermined pressures at the tip or periphery of the impeller 2, effecting a smooth streamline or uniform flow of the air as it leaves the main blades 7 of the impeller member and passes into the annular delivery chamber 14. This flow of auxiliary or boundary air at opposite sides of the casing and main airflow smooths out the main flow, eliminating recirculation or turbulence in the main flow with a corresponding greater efficiency in the operation and output of the impeller device.

The auxiliary air intake openings 12' and 13' may be somewhat restricted in area to produce a controlled flow of air, with a somewhat lower pressure area, intermediate the auxiliary inlet openings 12' and 13' and the discharge point at the periphery of the impeller member. This reduction in pressure between the sides 5 and 6 of the impeller and the sides of the casing reduces the frictional drag on side plates of the impeller, and even though the air delivered by the auxiliary blades 17 and 18 at opposite sides of the air flow from the main blades 7 may be under a lower compression than the main air flow, the auxiliary flow has a tendency to expand after leaving the tip of the impeller, as it merges with the main flow, will cause the aforementioned boundary layers at opposite sides of the main air flow to effect a smooth and uniform flow of the air flow as it passes into the annular chamber 14 and is discharged at 14' from the pump.

Referring to Fig. 1 of the drawing, one of the side plates of the impeller may also be apertured as indicated at 19 to provide inlet passages or openings admitting air or the fluid being pumped into the space between the side plate 6 and the adjacent surface of the impeller casing. These apertures 19 are located at points between the periphery of the impeller 2 and its central or hub portion 3 to provide means for introducing a portion of the fluid entering main throat 8 into the zone of the auxiliary blades 18 at the inner ends of these blades. The auxiliary blades 18 cause this air to be projected from between the impeller and casing at the periphery of impeller, at the side of the main flow, between the main flow and the impeller casing, eliminating the low pressure area usually occurring at the periphery of the impeller, and preventing the formation of eddies in the main flow where it leaves the rim of the impeller which ordinarily occur and cause turbulence in the main air flow. The front shrouds 5 may also be provided with openings similar to the openings 19 in the rear shrouds, if it is desired, but as the rim of the

central opening in the front shroud is located about at the point 13' where the inner ends of the vanes or ribs 17 are located the auxiliary air can readily be admitted through the narrow annular opening 13', into the space between the front shroud 5 and the adjacent inner surface of the casing in the zone of the front auxiliary blades 17.

A further modification of the invention is disclosed in Figs. 3 and 4 in which the impeller member, as indicated at 20, if formed with a rotary single flange or disc member 21 having main impeller blades 22 extending forwardly toward the front wall of the impeller housing, and auxiliary blades 23 projecting from the rear face of the impeller member 20 toward the rear wall of the impeller housing. The rear or auxiliary blades supply the auxiliary air flow or boundary layer to the rear portion of the main flow, as before described, with the same increased efficiency and lack of turbulence in the air flow at this point as previously set forth. Instead of utilizing a front shroud member with auxiliary blades thereon to supply the other or front boundary layer of air to the main air flow, I provide a plurality of tubular members 24 of a somewhat tapered and curved formation, substantially rectangular in cross section. These tubular members are preferably made of light sheet material and formed to fit into the spaces between the main impeller blades 23, with their sides 25 constructed and arranged to lie in spaced relation to the inner surface of the adjacent front wall of the impeller casing, when the impeller is positioned therein. The walls 25 of the tubular members 24 form and constitute a second shroud member in effect, with the extremities 26 of the main blades 22 projecting out beyond the walls 25 constituting, in effect, auxiliary blades or vanes adjacent the inner surface of the front wall of impeller casing providing means for supplying the other, or front boundary layer of air for the main air flow at the impeller periphery and as it leaves the impeller and enters the annular delivery chamber 14, eliminating any tendency for recirculation or turbulence in the main air flow.

Having thus described my invention, I claim,

1. In a high speed centrifugal impeller of the class described, a circular casing having opposite front and rear walls smoothly blending into an enlarged annular peripheral chamber, substantially circular in cross section, having a tangential fluid outlet, one of said walls having a central fluid inlet opening therein, an impeller member concentrically rotatable within the casing between the front and rear walls thereof comprising spaced annular shroud members having their peripheries disposed inwardly of the said annular peripheral chamber to leave an annular space between the periphery of the impeller and said peripheral chamber, and disposed in spaced relation to the side walls of the casing, one of said shroud members having a fluid inlet in register with the fluid inlet in the wall of the casing, main impeller blades extending between the shroud members of the impeller member, auxiliary unobstructed impeller blades projecting from said shroud members toward said front and rear walls of the casing for inducing an auxiliary boundary layer flow of the fluid being pumped, along each adjacent side wall of the casing to be delivered in a plane parallel to the plane of rotation of the impeller at the periphery of the impeller member at each side of the main fluid flow

from the main impeller blades between the same and the front and rear walls of the casing to provide a boundary fluid flow along the interior of the casing at opposite sides of the main fluid flow to eliminate turbulence in the fluid being pumped.

2. In a high speed centrifugal impeller of the turbo-blower type, a circular casing formed with an enlarged annular peripheral chamber, substantially circular in cross section and having spaced front and rear circular walls with their peripheral portions curving smoothly outwardly and merging into said annular chamber, said circular front wall having a substantially centrally located fluid inlet port, impeller means rotatably mounted within the casing comprising spaced annular side plates having their peripheries disposed radially inwardly of the said annular chamber and in spaced relation to the side walls of the casing to permit the fluid being pumped to flow therebetween, main impeller blades extending between the said impeller side plates, auxiliary impeller blades extending from the side plates and terminating in juxtaposed relation to the inner surfaces of the adjacent side walls of the casing, for inducing an auxiliary boundary flow of the fluid being pumped by the impeller to flow radially outward along each side wall between the same and the casing to deliver said auxiliary flow in a radial direction at the periphery of the impeller member uniformly along the sides of the casing at each side of the main fluid flow next to the casing side walls to reduce turbulence of the fluid being pumped as it leaves the impeller member and passes into the annular chamber, one of said impeller member side plates having radially inclined fluid conducting passages formed therein extending therethrough inwardly of its periphery between the auxiliary blades and intermediate the ends of the blades for establishing a fluid delivery conduit between the space between both impeller side plates, in the zone of the main and auxiliary impeller blades and the space between the side plate having the fluid conducting passages therethrough and the inner wall of the casing adjacent said latter plate.

3. A centrifugal impeller member for fluid pumps of the class described comprising a rotary shroud member having a plurality of main vane members projecting laterally from one face of the shroud member in a direction from the center to the periphery to form fluid passages therebetween and a plurality of auxiliary vane members projecting laterally from the opposite face of the shroud member in a direction from the center toward the periphery to form auxiliary fluid passages therebetween, insert members disposed on the impeller member between the main vane member, each having a wall extending between the adjacent main vane members in spaced relation to said shroud member and terminating in angular side portions disposed against the opposite faces of the main vane members with the walls of the insert members disposed in a plane located between the plane traversed by the lateral edges of the main impeller vanes and the adjacent surface of the shroud member to leave exterior auxiliary fluid conduits extending along the said insert members between the vane members, and an impeller casing, surrounding the said impeller member having side plates disposed adjacent the sides of the impeller member with the said auxiliary fluid inlet passages introducing boundary layers of the fluid being pumped at

opposite sides of the fluid passing through said insert members, introducing boundary layers of the pumped fluid flowing along the sides of the casing in the same direction as the main fluid flow.

4. A centrifugal impeller member for fluid pumps of the class described comprising a rotary shroud member having a plurality of main impeller vane members projecting laterally from one face of the shroud member and a plurality of auxiliary vane members projecting laterally from the opposite face of the shroud member, tubular insert members disposed on the impeller member between the main impeller vane members, each having an outer wall portion extending between 10

5 the adjacent vane members in spaced relation to the shroud member and to a plane passing through the lateral edges of the main vane members intermediate said edges and the shroud member, to form main fluid conduits within the tubular members, auxiliary boundary layer fluid conduits between the main vane members and the aforesaid edges, and an impeller casing, housing said impeller member having side plates disposed adjacent the sides of the impeller member and fluid inlet openings formed therein for introducing the fluid to be pumped at opposite sides of the impeller member, and into the interior of the tubular members.

ADOLPH L. BERGER.
